CLAIM

The ornamental design for a rearview mirror, as shown and described.

DESCRIPTION

FIG. 1 is a back perspective view of a rearview mirror according to a first embodiment of our design;

FIG. 2 is a front perspective view thereof;

FIG. 3 is a detail view thereof showing area 3, as indicated in FIG. 2;

FIG. 4 is a back elevation view thereof;

FIG. 5 is a front elevation view thereof;

FIG. 6 is a right side elevation view thereof;

FIG. 7 is a left side elevation view thereof;

FIG. 8 is a detail view thereof showing area 8 of FIG. 7, being enlarged for ease of illustration;

FIG. 9 is a top plan view thereof;

FIG. 10 is a bottom plan view thereof;

FIG. 11 is a detail view thereof showing area 11 of FIG. 10, being enlarged for ease of illustration;

FIG. 12 is a back perspective view of a rearview mirror according to a second embodiment of our design;

FIG. 13 is a front perspective view thereof;

FIG. 14 is a detail view thereof showing area 14 of FIG. 13, being enlarged for ease of illustration;

FIG. 15 is a back elevation view thereof;

FIG. 16 is a front elevation view thereof;

FIG. 17 is a right side elevation view thereof;

FIG. 18 is a left side elevation view thereof;

FIG. 19 is a detail view thereof showing area 19 of FIG. 18, being enlarged for ease of illustration;

FIG. 20 is a top plan view thereof;

FIG. 21 is a bottom plan view thereof; and,

FIG. 22 is a detail view thereof showing area 22 of FIG. 21, being enlarged for ease of illustration.

The dash-dash broken lines illustrate portions of the rearview mirror that form no part of the claimed design. The dash-dot-dot broken lines illustrate boundaries for the detail views and form no part of the claimed design.
